UNITED STATES PATENT OFFICE.

CHARLES ALBERT BALL, OF MARION, INDIANA.

DESIGN FOR A BADGE.

SPECIFICATION forming part of Design No. 21,644, dated June 21, 1892.

Application filed April 22, 1892. Serial No. 430,267. Term of patent 3½ years.

To all whom it may concern:

Be it known that I, CHARLES ALBERT BALL, a citizen of the United States, residing at Marion, in the county of Grant and State of Indiana, have invented and produced a new and original Design for Medals and Badges, of which the following is a specification, reference being had to the accompanying drawings, forming a part thereof, in which—

10 Figures 1 and 2 represent, respectively, the obverse and the reverse of a medal or badge embodying my new design.

The design is distinguished by its general effect, and the drawings are mainly relied 15 upon to elucidate its general features, the following general description being given for the purpose of this specification.

The figure of an eagle is represented as crouching above a ribbon-like panel and as 20 supporting an olive branch, the ribbon-like panel or figure being decorated with a representation simulating the coat of arms of the United States. There is represented as sus-

pended beneath the ribbon-like panel a disk or medallion, ornamented upon its obverse 25 side with a pictorial representation of the landing of Columbus. The reverse side of the disk or medallion, represented as suspended from the ribbon-like panel, is decorated with the representation of a building simulating the Administration Building of the 30 Columbian Exposition.

I claim—

1. The design for the medal or badge, substantially as herein shown and described. 35
2. In the design for the medal or badge, the obverse side, substantially as herein shown and described.
3. In the design for the medal or badge, the reverse side, substantially as herein shown 40 and described.

CHARLES ALBERT BALL.
